DESIGN FOR A CONNECTION BOX OR SIMILAR ARTICLE

Charles G. Hose, Rockville Centre, N. Y., assignor to Hose-McCann Corp., Brooklyn, N. Y., a corporation of New York

Application July 16, 1941, Serial No. 102,180

Term of patent 7 years

To all whom it may concern:

Be it known that I, Charles G. Hose, a citizen of the United States, residing in Rockville Centre, County of Nassau, and State of New York, have invented a new, original, and ornamental Design for a Connection Box or Similar Article, of which the following is a specification, reference being had to the accompanying drawing, forming part thereof.

nection box showing my new design.

the cover open.

The rear of the connection box is plain.

I claim:

The ornamental design for a connection box
or similar article, as shown and described.

CHARLES G. HOSE.
